UNITED STATES PATENT OFFICE.

MICHAEL A. ROLLMAN, OF MOUNT JOY, PENNSYLVANIA.

DESIGN FOR A SADIRON.

Application filed September 13, 1927. Serial No. 23,399. Term of patent 14 years.

To all whom it may concern:

Be it known that I, MICHAEL A. ROLLMAN, a citizen of the United States, residing at Mount Joy, in the county of Lancaster and State of Pennsylvania, have invented a new, original, and ornamental Design for Sad- irons, of which the following is a specifica- tion, reference being had to the accompany- ing drawing, forming part thereof.

The figure is a front perspective view of a sadiron, showing my new design.

The dominant feature is the handle having a corrugated effect.

I claim:

The ornamental design for a sadiron, as shown and described.

MICHAEL A. ROLLMAN.
